Specification for Design.

Patented Apr. 25, 1911.

Application filed February 9, 1911. Serial No. 607,704. Term of patent 7 years.

To all whom it may concern:

Be it known that I, FISHER H. LIPPINCOTT, a citizen of the United States, residing in the city of Philadelphia, county of Philadelphia, and State of Pennsylvania, have invented a new, original, and ornamental Design for Soda-Fountains, of which the following is a specification.

The drawing is an elevation of a soda fountain embodying my design.

The drawing illustrates a soda fountain comprising a pedestal 1, a globe 2 on the

pedestal, an urn 3 above the globe, an arm 4 extending laterally from the globe, a nozzle 5 on the arm, an arm 6 on the nozzle, and a shaft 7 and wheel 8 above the nozzle.

I claim:

The ornamental design for a soda fountain substantially as shown and described.
